ROLLAND F. SHERFY, OF WASHINGTON, DISTRICT OF COLUMBIA

VARIABLE CONDENSER

Application filed September 21, 1927. Serial No. 220,982.

(GRANTED UNDER THE ACT OF MARCH 3, 1883, AS AMENDED APRIL 30, 1928; 370 O. G. 757)

My invention relates broadly to variable condensers and more particularly to variable condensers for use in high frequency radio apparatus.

5 The object of my invention is to provide a condenser that is compact in size, accurate in capacity adjustment and free from inherent inductance.

10 Another object of my invention is to produce a condenser in which there are no losses occasioned by dead ends.

15 A further object of my invention is to produce a variable condenser that is free from the effects of "hand capacity" when adjustment is required.

20 Further objects of my invention will appear more fully hereinafter as the description of the method and apparatus is developed.

25 My invention consists substantially in the construction, combination and arrangement of parts associated therewith or as will be more fully hereinafter set forth as shown by the accompanying drawings and finally pointed out in the appended claims.

Reference is to be had to the accompanying drawings forming a part of this specification in which like reference characters indicate corresponding parts throughout the 30 several views and in which:

Figure 1 is a perspective view of my improved condenser.

Figure 2 is a sectional view on the plane XXXX of Figure 1, and

35 Figure 3 is a modification thereof.

Referring to the drawings numeral 1 represents a base upon which are mounted two upright members 2 and 3. The members 2 and 3 are held firmly in a fixed upright 40 position by means of brackets 4 that are secured thereto and to the base 1 by means of bolts 5.

45 Between the two upright members are mounted two rolls 6 and 7 of insulating material that are rotatable on bearings 7' in the upright members 2 and 3. These bearings are so positioned that the distance between the centers of the rolls is that of the diameter of one of the rolls plus the 50 thickness of the sheets of metal foil 8 and

9 and the thickness of the dielectric material 10.

The two rolls are rotated together by means of intermeshed gear 11 and 12 that are mounted upon the ends of the rolls. 55 The control of the rotation of the rolls is accomplished by means of a dial 13 or any other suitable means which is mounted upon an extension 14 of one of the rolls.

Referring particularly to Figure 2 the 60 metal foil is wound upon the rolls in such a manner that, as the films leave the rolls, the foils move in a parallel relation to each other. The inner ends of the films are secured to the rolls by the insertion of the end 65 of each in a groove 15 in each of the rolls. The outer ends of the films are mechanically secured to each other and to the sheet of dielectric material 10 by means of clamps 16 and 17 which are held in position by means 70 of bolts 18. A portion of the films is cut away around the bolts 18 to prevent electrical contact between the bolts and the films 8 and 9 which would produce a short circuit within the condenser. 75

Attached to the clamps 16 and 17 and the brackets 4 are strips 17a of resilient material such as elastic rubber, springs or the like that maintain the strips of the unrolled films in a vertical position and also maintain the portions of the films that are wound upon the rolls in immediate electrical contact with the preceding layers. 80

Electrical contact is made with the individual films by means of brushes 19 and 20 that rest firmly against the surface of each film and are in electrical contact with the terminal blocks 23 and 24 of the condenser. A spring member encased as at 22 has an arm 25 bearing against roller 6 in order to 85 keep the rollers 6 and 7 close together at all times. 90

Figure 3 represents a modification of my invention in which the sheet of dielectric 95 10 is firmly fixed in a vertical position between the upright supporting members 2 and 3. The mounting is accomplished by means of bracket plates 4' that are secured to the corners of the dielectric sheet 10 and to the upright members. The sheet of dielectric 100

contains a plurality of perforations 21 through which extend the bolts 18 on the clamp 16. These perforations not only permit the movement of the foil along the sides 25 of the sheet of the dielectric but also serve as guides for the ends of the foil.

In the practical construction of the apparatus as shown in Figure 3 in the modification, I desire to utilize sheets of metal foil 10 made up of thin sheet brass or other suitable metals of about 1/500ths of an inch thickness. The rolls 6 and 7 and the dielectric material 10 I construct of a resilient insulating material, preferably rubber, that is 15 capable of contraction and expansion whereby the thin foils 8 and 9 can be rolled upon rolls 6 and 7 and will remain in parallel relation to each other at all times due to the 20 flexibility of the material making up the rolls, which compensate for the slight thickness caused in the rolling of the foils.

It should be noted that in either of the types of condenser described the use of a dielectric other than air may be eliminated 25 and guides provided at the edges of the foils for maintaining them in their parallel relationship to each other.

From the description of the apparatus it is to be noted that I have produced a condenser that has no losses due to "dead ends" 30 for by the construction shown the rolls of the metallic film constitute merely a terminal for the brushes as the individual turns of the metallic films are short circuited. Furthermore I have produced a condenser in which 35 there is no "hand capacity effect" for the reason that any adjustments of the capacity of the condenser is made from the sides of the plates of the condenser which arrangement reduces the "hand capacity effect" to a 40 minimum.

It will be understood that the above description and accompanying drawings comprehend only the general and preferred embodiment of my invention and that minor detail changes in the construction and arrangement of parts may be made within the scope of the appended claims without sacrificing any of the advantages of my invention. 50

The invention herein described may be manufactured and used by or for the Government of the United States for governmental purposes without the payment to me of any royalty thereon or therefor.

Having thus described my invention, what I claim is as follows:

1. In a variable condenser, a base, supporting members secured thereto, rolls, metallic films mounted on said rolls and between said members, means securing the free ends of said films together, and means for simultaneously rolling and unrolling 65 said films in parallel planar relation to vary

the capacity and to form a condenser substantially planar.

2. In a variable condenser, a base having supporting members secured thereto, rolls mounted between said members, metallic 70 films having one of their ends fastened to each of said rolls, a dielectric between said rolls and separating said films, means for securing the free ends of said films to said dielectric and means for simultaneously 75 rolling and unrolling said films on said rolls in parallel planar relation to vary the capacity and to form a condenser substantially planar.

3. In a variable condenser, a base having so supporting members secured thereto, rolls mounted for rotation between said members, metallic foil having one of their ends fastened into said rolls, a dielectric sheet between said foils means to maintain the centers of said rolls spaced apart a distance substantially that of the diameter of one of said rolls plus the thickness of the foil around said rolls, and the dielectric sheet and means for simultaneously rolling and 90 unrolling said foil on said rolls in parallel planar relation to vary the capacity and to form a condenser substantially planar.

4. In a variable condenser, a base having supporting members secured thereto, rolls mounted for rotation between said members, metallic foils having one of their ends fastened to each of said rolls and the free ends thereof clamped together, a dielectric sheet between said foils means to maintain the centers of said rolls spaced apart a distance substantially the diameter of one of said rolls plus the thickness of said foil around said rolls, and the dielectric sheet and means for simultaneously rolling and 105 unrolling said foil on said rolls in parallel planar relation along the faces of the dielectric sheet to vary the capacity and to form a condenser substantially planar.

5. In a variable condenser a base, supporting members secured thereto, rolls mounted for rotation between said members, metallic foils having one of their ends fastened to said rolls and the free ends thereof clamped together, a dielectric sheet 110 between said foils and means for simultaneously rolling and unrolling said foil on said rolls in parallel planar relation along the faces of the dielectric sheet to vary the capacity and to form a condenser substantially planar.

6. In a variable condenser a base, supporting members secured thereto, rolls mounted for rotation between said members, metallic foils having one of their ends fastened to said rolls and the free ends thereof clamped together, a dielectric sheet between said foils, means for simultaneously rolling and unrolling said foil on said rolls in 125 parallel planar relation along the faces of

the dielectric sheet to vary the capacity and to form a condenser substantially planar, said means comprising a gear on each of the rolls, and means for rotating said gears.

- 5 7. In a variable condenser, a base, supporting members secured thereto, rolls mounted for rotation between said members, metallic foils having one of their ends fastened to said rolls, means securing the free 10 ends of said foils together, a dielectric sheet between said foils, means for simultaneously rolling and unrolling said foils on said rolls in parallel planar relation to vary the capacity and means for maintaining the foils in 15 their parallel relation to form a condenser substantially planar.

8. In a variable condenser, a base, supporting members secured thereto, rolls mounted for rotation between said members, 20 metallic foils having one of their ends fastened to said rolls, means securing the free ends of said foils together, a dielectric sheet between said foils, means for simultaneously rolling and unrolling said foils on said rolls 25 in parallel planar relation to vary the capacity and means for maintaining the foils in their parallel relation to form a condenser substantially planar, said means consisting of an elastic element exerting a tension upon 30 the clamped ends of said foil.

9. In a variable condenser, a base, supporting members secured thereto, rolls mounted for rotation between said members, metallic foils having one of their ends secured to the rolls, a dielectric sheet between 35 said foils, means mechanically clamping the free ends of the foils rigidly in a fixed position relative to each other and insulated from each other by said dielectric, means 40 for rolling and unrolling said foil on said rolls in parallel planar relation to each other to vary the capacity of the condenser, and means for maintaining the foils in their parallel relation to form a condenser substantially planar.

10. In a variable condenser, a base, supporting members secured thereto, rolls, metallic films mounted on said rolls and between 50 said members, means securing the free ends of said films together, means for simultaneously rolling and unrolling said films in parallel planar relation to vary the capacity and to form a condenser substantially planar, and brushes engaging the metallic foils and constituting the terminals 55 of the condenser.

11. In a variable condenser, a base, supporting members secured thereto, a pair of 60 rolls mounted for rotation between said members, metallic foils having one of their ends secured to each of said rolls, respectively, a dielectric sheet between said rolls, and means mechanically clamping the free 65 ends of said foils rigidly in a fixed position

relative to each other and insulated from each other by said dielectric sheet.

12. In a variable condenser, a base, supporting members secured thereto, a pair of rolls mounted for rotation between said members, metallic foils having one of their ends secured to each of said rolls, respectively, a dielectric sheet between said rolls, means mechanically clamping the free ends of said foils rigidly in a fixed position relative to each other and insulated from each other by said dielectric sheet, and means varying the effective area of said foils comprising a gear on each roll and means for rotating said gears.

13. In a variable condenser, a base having supporting members secured thereto, rolls mounted for rotation between said members, metallic foils having one of their ends secured to each of said rolls, a dielectric sheet between said rolls, means mechanically clamping the free ends of said foils rigidly in a fixed position to each other and insulated from each other by said dielectric sheet, means varying the effective area of said foils and means holding said foils in their parallel planar relation during the variation of the capacity of the condenser to form a condenser substantially planar.

14. In a variable condenser, a base having supporting members secured thereto, rolls mounted for rotation between said members, metallic foils having one of their ends secured to each of said rolls, a dielectric sheet between said rolls, means mechanically clamping the free ends of said foils rigidly in a fixed position to each other and insulated from each other by said dielectric sheet, means varying the effective area of said foils, means holding said foils in their parallel planar relation during the variation of the capacity of the condenser to form a condenser substantially planar and brushes engaging said foils and constituting the terminal of the condenser.
